[57] CLAIM

The ornamental design for a table, as shown and described.

DESCRIPTION

FIG. 1 is a perspective view of a table showing my new design;

FIG. 2 is a side elevational view thereof;

FIG. 3 is a top view thereof;

FIG. 4 is an end elevational view thereof, and

FIG. 5 is a bottom view thereof.

The broken lines representing casters supporting the table are shown for illustrative purposes only.
